UNITED STATES PATENT OFFICE.

JESSE M. LILLPOP, OF KYANA, INDIANA, ASSIGNOR OF ONE-HALF TO HARRISON L. WHEAT, OF SAME PLACE.

VEGETABLE-CUTTER.

SPECIFICATION forming part of Letters Patent No. 427,096, dated May 6, 1890.

Application filed March 26, 1889. Serial No. 304,811. (No model.)

To all whom it may concern:

Be it known that I, JESSE M. LILLPOP, a citizen of the United States, residing at Kyana, in the county of Dubois and State of Indiana, have invented certain new and useful Improvements in Vegetable-Cutters; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to vegetable-cutters, and has for its object to furnish a cutter for sauer-kraut or slaw which shall be simple in construction, reliable in use, not liable to get out of order, and capable of being taken 20 apart and packed away in a small compass when not in use.

With this object in view my invention consists in the improved construction, arrangement, and combination of parts, hereinafter 25 fully described, and afterward pointed out in the claims.

In the accompanying drawings, Figure 1 is a view in side elevation of a kraut-cutter made in accordance with my invention, mounted 30 ready for use on a barrel, the lower portion of the barrel and part of one of the uprights being broken away. Fig. 2 is a view of the same in vertical section. Fig. 3 is an enlarged bottom plan view of the knife-plate 35 which forms the bottom of the cylinder when the cutter is ready for use. Fig. 4 is a fragmentary sectional view through one of the knives and a portion of the knife-plate. Fig. 5 is a perspective view of the horizontal driv- 40 ing-shaft and its bevel-gear. Fig. 6 is a perspective view of the knife-plate, the central shaft secured thereto, and its bevel-gear removed from the machine. Fig. 7 is a perspective view of the weight-plate removed 45 from the machine.

Like letters of reference mark the same parts wherever they occur in the various figures of the drawings.

Referring to the drawings by letters of reference, A is a cylinder, formed of any desired

material, sheet metal preferred, which is open at top and bottom, as shown.

B is a plate, which when in position for use forms a bottom for said cylinder. This plate has secured to it a central vertical shaft C, 55 which extends above and below the plate, and at the bottom is stepped in a plate D, let into and secured to a cross-beam E, said cross-beam being of a length to allow it to rest in the top of a barrel or other receptacle F. 60 This cross-beam passes through two uprights G H, set apart a distance slightly greater than the width of the cylinder A. Mounted in the outer angles formed by the cross-beam and uprights and resting against each are two 65 cross-beams at right angles to the cross-beams I J, through which are projected pins K to hold the parts in position on the barrel. In bearings formed in the top of the uprights G H is a horizontal shaft L, having rigidly 70 secured to it a crank or handle M and a bevel-gear N. This bevel-gear N engages a bevel-gear O on upright shaft C, so that rotation of the shaft L will serve to rotate the vertical shaft and its attached knife-plate.

Secured to each side of the open cylinder A are ears P, which are bent around the uprights, thus holding the parts in place.

The upright shaft near its upper end passes 80 through a cross-beam Q, whose ends are formed to correspond with the inside of the uprights G H, and its length is just the proper distance between those uprights. The inside thereof and the ends of the beam Q may be formed with tongues and grooves as desired, one construction of which is shown in Fig. 1 of the drawings and another in Fig. 2. The horizontal shaft L at one end is turned down, forming a journal a and a shoulder b. This journal has its bearing in a hole c in the upper 90 end of the upright H. The other journal of the shaft L is formed at d with two shoulders e f, rests in a slot g in top of upright G, and is held against displacement by a pin h passing through the walls of said slot.

As before stated, the knife-plate forms the bottom of the cylinder. There is also provided a weighted or heavy plate R, which is slotted radially at S from its circumference to its center T, so that it may be passed 95 100

upon the upright shaft above the cylinder and dropped down upon the cabbage or other matter in the cylinder, keeping it pressed down upon the knife-plate. This 5 knife-plate is radially slotted, as at *i*, to receive any desired number of knives *k*, as shown in Figs. 3 and 4, such slots having one under side, as at *l*, beveled or inclined, and the other, as at *m*, straight. The knives *k* 10 are slotted, as at *n* in Fig. 3, and held upon the inclined sides of the grooves, with their edges passed slightly above the surface of the knife-plate, by means of a screw *p* passing through said slots and into the plate, thus 15 permitting any desired adjustment of the knives therein.

The operation of my invention is as follows: It being desired to cut slaw or kraut, the cutter is placed on a barrel or other receptacle 20 in the manner shown and described, cabbage placed in the cylinder resting on the knife-plate, and the weight-plate placed on top of it. By turning the handle the horizontal shaft is rotated, carrying with it the vertical shaft, 25 causing the knife-plate with its projecting knives to rotate and shave off strips from the bottom of the cabbage, which pass through the slots into the barrel below, the weight-plate keeping the cabbage down upon the 30 knives at all times. The operation being finished, the whole machine may be taken apart by withdrawing a few pins, and stored away until again wanted.

Having thus fully described my invention, 35 what I claim as new, and desire to secure by Letters Patent of the United States, is—

1. In combination, the knockdown frame consisting of side uprights, a bottom cross-

beam and an upper cross-beam fitted removably and sliding vertically between the uprights, the open-ended cylinder having side ears for bending around the uprights, the knife-plate forming the bottom of said cylinder, a vertical shaft carrying said knife-plate, having a step bearing in the lower cross-beam, and suitable means for rotating said vertical shaft and passing through the upper cross-beam, substantially as set forth. 40 45

2. In combination, a knockdown frame, an open-ended cylinder provided with ears for attachment to said frame, a vertical shaft carrying a knife-plate which forms the bottom of said cylinder, and a radially-slotted weight-plate which when in use forms the cover for the material being operated upon in said cylinder. 50 55

3. A knockdown vegetable-cutter consisting of the combination of uprights *G*, horizontal beam *E*, passing through said uprights, horizontal beams *J* at right angles to beam *E*, 60 provided with pins *K*, an open-ended cylinder removably secured between the uprights, a vertical shaft stepped in cross-beam *E* and carrying knife-plate, removable weighted plate *R* on said shaft, removable cross-beam 65 *Q*, through which the vertical shaft passes, and a horizontal shaft geared to the vertical shaft removably journaled in the uprights *G* and *H*, all substantially as set forth.

In testimony whereof I affix my signature 70 in presence of two witnesses.

JESSE M. LILLPOP.
